CONTAINER

Thomas E. Sikes, Greensboro, N. C.

Application May 12, 1938, Serial No. 207,617

3 Claims. (Cl. 217—14)

This invention relates to containers, and has for one of its objects the production of a simple and efficient folding container which may be conveniently folded to occupy a minimum amount of space and which, when set up, will provide a sturdy, well braced and economical container for shipping tobacco and other products.

A further object of this invention is the production of a folding container having a specially constructed hinge connection for the walls or panels thereof to facilitate the folding of the panels or wells in snug compact relation to accommodate a minimum amount of space in storage, or when the container is being shipped empty.

Another object of this invention is the production of a folding container having efficient means for locking and bracing the panels or walls in set-up relation to prevent the walls or panels from collapsing while the container is being used for shipment of tobacco, other products, and articles constituting the contents thereof.

Other objects and advantages of this invention will appear throughout the following specification and claims.

In the drawings:

Figure 1 is an end elevational view of the container;

Figure 2 is a sectional view taken on line 2—2 of Figure 1;

Figure 3 is a sectional view taken on line 3—3 of Figure 2;

Figure 4 is a horizontal sectional view taken on line 4—4 of Figure 1;

Figure 5 is a bottom plan view of the container;

Figure 6 is a top plan view of the container in a folded position;

Figure 7 is an end elevational view of the container in a folded position;

Figure 8 is a horizontal sectional view of the container in a folded position looking toward the top of the container;

Figure 9 is an enlarged horizontal sectional view looking toward the bottom of the container;

Figure 10 is a vertical sectional view taken on line 10—10 of Figure 6;

Figure 11 is an enlarged sectional view taken on line 11—11 of Figure 9;

Figure 12 is a bottom plan view of the container in a folded position;

Figure 13 is a horizontal sectional view taken on line 13—13 of Figure 12;

Figure 14 is a sectional perspective view taken on line 14—14 of Figure 2;

Figure 15 is a sectional perspective view taken on line 15—15 of Figure 2;

Figure 16 is a sectional perspective view of a portion of one of the side walls of the container, showing one of the locking tongues, which tongues are adapted to engage the bottom when the container is in a set-up position;

Figure 17 is an inverted sectional perspective view of a portion of the bottom of the container showing one of the sockets which is adapted to be engaged by the tongues carried by the walls of the container;

Figure 18 is a front elevational view of the hasp lock used with the present container;

Figure 19 is a vertical sectional view taken on line 19—19 of Figure 18;

Figure 20 is a vertical sectional view showing a modified form of lid or cover locking means;

Figure 21 is a horizontal sectional view taken on line 21—21 of Figure 20;

Figure 22 is a top plan view of a further modified form of the container, the cover or lid being shown in an open position;

Figure 23 is a top plan view of the container shown in Figure 22 in a folded position;

Figure 24 is a vertical sectional view taken on line 24—24 of Figure 23;

Figure 25 is a perspective view of a further modified form of the container of the open-end type;

Figure 26 is an enlarged vertical sectional view taken on line 26—26 of Figure 25;

Figure 27 is an end elevational view of a still further modified form of the container;

Figure 28 is a side elevational view of the form 35 of the container shown in Figure 27;

Figure 29 is a vertical sectional view taken on line 29—29 of Figure 28;

Figure 30 is an irregular sectional perspective view taken on line 30—30 of Figure 28;

Figure 31 is a top plan view of another modified form of container showing a bi-sected bottom, the lid being shown partly broken away;

Figure 32 is a sectional view taken on line 32—32 of Figure 31;

Figure 33 is a sectional view taken on line 33—33 of Figure 32;

Figure 34 is a fragmentary longitudinal sectional view through a portion of the container showing a modified type of bottom securing 50 means;

Figure 35 is a vertical sectional view taken on line 35—35 of Figure 34;

Figure 36 is a fragmentary top plan view of a modified type of hinge structure for connect- 55

ing the top to one of the side walls of the container;

Figure 37 is a transverse sectional view taken on line 37—37 of Figure 36;

5 **5** Figure 38 is a fragmentary top plan view of a modified type of container having each side wall thereof connected to the end walls by means of alternate straight and off-set hinges.

By referring to the drawings, it will be seen 10 that A designates the container, which comprises a pair of side walls 1 and sectional end walls 2. Each end wall 2 comprises sections 2^a and 2^b, which are vertically hinged together to fold inwardly of the container A by means of a hinge 3.

15 The sections 2^a and 2^b of the end walls 2 are hingedly secured to the ends of the side walls 1 by means of inset hinges 4, which are so constructed as to hingedly support the end walls 2 inwardly of the inner faces of the side walls 1 and permit the end walls 2 to be freely folded 20 inwardly of the container A, as shown in Figure 6, when the container is in a folded or knock-down position.

Each inset hinge 4 comprises a section 4^a 25 which is substantially U-shaped in cross-section, fitting over the ends of the walls 1, as shown in Figure 4, and having a right-angularly and inwardly extending pintle-receiving portion 5 spaced inwardly of the inner faces of the side walls 1. Each sectional end wall 2 carries a hinge section 4^b along its edge adjacent the side walls 1 for receiving the pintle pins 6 in inter-fitting relation with the sections 4^a, thereby 30 hingedly connecting the walls 1 and 2 together. These hinges 4 are preferably formed of thin 35 sheet metal and form a metal reinforcing binding for the side edges of the walls 1 and 2, which walls may be made of any suitable or desired material without departing from the spirit of the invention.

The sections 2^a and 2^b are provided with U-shaped metal binding strips 7 along the top and inner edges thereof, as indicated in Figures 1 and 4. The sections 2^a and 2^b are also provided 40 with U-shaped metal binding strips 8 along the bottom edges thereof and these strips 8 are provided with ledge portions 9 extending inwardly of the container A, as shown in Figure 2. One side wall 1 is provided with a U-shaped metal binding strip 10 along its bottom edge and carries 45 a ledge portion 11 extending inwardly of the container A, as shown in detail in Figure 14. The opposite side wall 1 carries an inset hinge 12 along its lower edge, to which is secured one 50 edge of the bottom 13 in a manner whereby the bottom 13 may be folded inwardly of the container A, as shown in Figures 6, 8 and 9, and lie flat and snugly against the side wall 1 to which it is hinged, when the container is in a folded 55 position. When the container A is in a set-up position, the outer edges of the bottom 13 rest upon the ledges 9 and 11, which ledges 9 and 11 will constitute a support for the bottom 13 as 60 will be obvious by considering Figure 2. Locking levers 14 are pivotally secured to the inner 65 face of one of the side walls 1 and engage the bottom 13 near the outer edge thereof for firmly holding the bottom 13 in engagement with the ledges 9 and 11 when the container A is in a set-up position. Stop pins 15 are carried by the 70 side walls 1 to limit the swinging of the levers 14 in one direction.

Each of the ledges 9 and 11 is provided intermediate its ends with an upwardly bent tongue 16, which upwardly bent tongue 16 is formed by 75 cutting two parallel slits 17 in the ledge and

then bending the tongue 16 upwardly or inwardly of the container A in a manner shown in detail in Figures 15 and 16. The bottom 13 is provided with a U-shaped metallic binding strip 18 along its side and outer edges, and this strip is notched, as at 19 at proper locations upon its under face to receive the tongues 16 of the ledges 9 and 11 when the bottom 13 is swung to an operative position in engagement with the ledges 9 and 11, the tongues 16 providing means for tying the side and end walls to the bottom and preventing the outward bulging of the walls with respect to the edges of the bottom when the box is in a set-up position.

A lid 20 is hingedly secured, as at 21, to one 15 of the side walls 1, and is adapted to cover the upper end of the box, and this lid is provided with a metallic binding 22 around its edges the outer and end edges of the binding 22 being provided with overhanging ledge portions, which 20 ledge portions 23 are adapted to overhang the lid upon the upper edges of the end walls 2 and the forward side wall 1, as shown in Figure 3.

A hasp 24 is carried by the lid 20 and engages 25 a keeper 25 carried by one of the side walls 1, the keeper 25 carrying a ring 26 which may be extended through the opening 27 formed in the hasp for opening the hasp, the ring 26 normally holding the hasp against accidental displacement 30 from the keeper when in the position shown in Figures 18 and 19.

By considering Figures 2, 3, 4 and 5, the manner in which the box is held in a set-up position will be obvious. When it is desired to fold the 35 box, the bottom 13 is swung inwardly so as to lie flat against one of the side walls 1. The end walls 2 are then folded inwardly, as shown in Figure 6 to fit against the bottom 13, as shown in Figure 6, thereby bringing the two side walls 40 1 close together, and the lid 20 is then folded back flat against the adjacent side wall 1 as is also shown in Figure 6. The locking levers 14 are also swung at right angles to the position shown in Figure 2 so as to extend in the position shown in dotted lines in Figure 2, and in full lines in Figure 6. By considering Figure 6 it will be seen that the box may be folded to accommodate itself to a minimum amount of space.

In Figures 20 and 21, there is shown a modified 50 type of lid locking device wherein the numeral 28 designates the folding box of a type similar to that previously described, having a lid 29, the lid being provided with a metallic edge binding 30 substantially U-shaped in cross-section, and 55 having a depending or inwardly extending flange 31 which is adapted to fit within the open end of the box 28, as shown in Figure 20. The binding 30 is also provided with an overhanging ledge portion 32 which is adapted to rest upon the upper or outer edge of the box, as shown in Figure 20. A rotating locking device 33 of any suitable type, either of the key type or otherwise, is carried centrally of the lid 29, and this rotating locking device is provided with a circular head-plate 34 fitting against the under face of the lid 29 and to which are pivotally secured radiating locking rods 35 which rods 35 extend through the flange 31, as shown in Figures 20 and 21, and are adapted to fit into the sockets 36 and 37 formed in the front wall 38 of the 70 box 28, and the end walls 39, as shown in Figure 1.

In Figures 22, 23 and 24, there is shown a still further modified type of the container consisting of a front wall 40 and a rear wall 41, which walls 75

40 and 41 are connected at their ends to single-panel end walls 42 through the medium of inset hinges 43 similar to the hinges described with respect to that form shown in Figures 1, 2 and 3. A 5 bottom 44 is hingedly connected, as at 45, by means of an inset hinge to the front wall 40 and is adapted to swing inwardly of the front wall 40 when the box is folded in the manner as shown in Figure 23, one of the end walls 42 being 10 adapted to fold over the box 44, and the other end wall 42 being adapted to extend beyond the front wall 40. The container is provided with means for locking the bottom in position when the container is in a set-up position similar to 15 the structure shown in Figures 2 and 15. The locking levers are indicated by the numeral 14^a and the retaining tongues are indicated in dotted lines by the numeral 16^a. A lid 46 is hingedly secured to the rear wall 41, as shown in Figures 20 22, 23 and 24. By considering Figures 23 and 24, the manner in which the box may be folded will be obvious.

In Figures 25 and 26, I have shown a type of box having an open upper or outer end, the box 25 being of a structure similar to that described with respect to Figure 23 in general with the exception that the box is arranged to permit the stacking of one box upon the other. I have indicated in Figures 25 and 26 the structure of one complete 30 box and a fragment of another box upon which the complete box is placed in stacked relation. It will be noted that the numeral 47 indicates one box which is provided along its lower edge with a downwardly extending flange or tongue 35 48, which tongue 48 is adapted to fit against the inner face 49 of the wall 50 of the lower box 51. In this way the stacking of one box upon the other will be facilitated.

In Figures 27, 28 and 29 and 30, I have shown another modified type of invention wherein the 40 container comprises front and rear walls 52 and 53, and end walls 54. A bottom 55 is provided similar to the bottom 13, and a lid 56 is also provided similar to the lid 20. The end walls 54 may be connected to the front and rear walls 45 52 and 53 by inset sectional hinges 57, as shown. The front and rear walls 52 and 53 are provided with centrally located vertically extending bracing strips 58 which strips are provided with outwardly pressed reinforcing beads 59.

In Figures 31, 32 and 33, I have shown still another form of the invention wherein a container 60 similar to the container A is shown with the exception that the container is provided with 55 a hinged or bisected bottom 61 so constructed as to allow the hinged sections of the bottom to swing inwardly in the manner as indicated in Figure 32, the bottom, when the box is in a set-up position, resting upon the ledge portions 62. The ledge portions 62 are provided with inwardly 60 extending tongues 63 similar to the tongues 16 for fitting in the notches 64 in the edge of the bottom 61 similar to the notches 19 previously described.

65 It should be understood that the walls may be made of any suitable or desired material and may be made solid, perforated, or even of the wire mesh type, without departing from the spirit of the invention, and it is not desired to limit the present invention to any particular type of 70 material which may be used. The important

features of the present invention, however, consist in the means which permits of the folding of the container to accommodate itself to a minimum amount of space and which also provides an efficient bracing means for holding the box 5 rigidly in a set-up position to prevent the walls from collapsing, providing at the same time, a light sturdy and inexpensive structure.

By referring to Figures 34 and 35, it will be seen that a slightly different type of bottom se- 10 curing means is provided in the nature of a hinged locking member 14^a which is hingedly secured to one of the side walls 1^a, as at 15^a. The bottom end of the locking member 14^a is adapted to rest against the bottom 13^a for holding the 15 same in a locked position in substantially the same manner as the locking device 14.

In Figures 36 and 37, I have shown a double hinge 21^a for connecting the lid 20^a to one of the 20 side walls 1^b.

In Figure 38, I have shown a type of box wherein each side wall 65 is provided with an offset hinged 66 at one end, and a straight hinge 67 at the other end for engaging the end walls 68.

Having described the invention, what I claim 25 is:

1. A folding container comprising side and end walls, the side and end walls being foldable with respect to each other, a bottom pivotally carried by one wall, bindings for the other walls having 30 inwardly extending portions constituting supporting ledges upon which the bottom is adapted to rest when the container is in a set-up position, means for engaging the bottom and releasably holding the same in a clamped engagement 35 with the ledges, and tongues cut from said ledges and bent upwardly for engaging the bottom and locking the bottom and walls in anchored relation.

2. A folding container comprising side and end 40 walls, the side and end walls being foldable with respect to each other, a bottom carried by one wall, bindings for the other walls having inwardly extending portions constituting supporting ledges upon which the bottom is adapted to rest when the container is in a set-up position, a binding for the edges of the bottom, the edges of the bottom having pockets formed therein, the binding for the edges resting upon the ledges, the binding for the bottom being formed with 45 openings constituting entrances for the pockets, and said ledges being cut to form tongues bent upwardly and passing through the openings in the binding and into the pockets for holding the 50 bottom and walls in anchored interlocking relation.

3. A folding container comprising side and end walls, the side and end walls being foldable with respect to each other, a bottom carried by one wall, the other walls having supporting ledges 60 upon which the bottom is adapted to rest when the container is in a set-up position, and said ledges having upstanding tongues, the bottom formed with recesses in its margins and a binding for the bottom formed with openings registering 65 with the recesses and together therewith forming pockets for receiving said tongues whereby said walls and bottom will be held in interlocked relation when said container is in a set-up position.

70
THOMAS E. SIKES.
